UNITED STATES PATENT OFFICE.

WALKER REYNOLDS, OF ANNISTON, ALABAMA, ASSIGNOR TO ALABAMA PIPE COMPANY, A CORPORATION OF ALABAMA.

PIPE JOINT.

Application filed October 4, 1926. Serial No. 139,359.

This invention relates to pipe joints of either the bell-and-spigot or the substantially equivalent sleeve or collar type, and has more particular reference to such joints in connection with which a malleable metal, such as 5 lead, and a fibrous material, such as jute or hemp, are employed together with some form of filler, for rendering the joint tight.

A primary object of the present invention 10 is to produce a pipe joint of the bell-and-spigot or other equivalent type, in which the base of the bell is occupied by a filler, preferably of metal or the like, the mouth of the bell is sealed with malleable material, and fibrous 15 material is interposed between said filler and said malleable material; and in which the surface of the filler that is opposed to the fibrous material is so shaped as to accentuate the tendency of said material to be forced out- 20 ward toward the inner surface of the bell, and inward toward the outer surface of the spigot, when the malleable material at the mouth of the bell is calked, or otherwise similarly forced into place.

25 A further object is to employ for the said filler a unitary ring of substantially unyielding material, having a substantially symmetrical, wedge-shaped edge which is adapted to be opposed to the fibrous material.

30 Another object is so to design and arrange the parts comprising the joint that the filler ring may fit loosely within the bell, and may fit loosely over the spigot, so that said parts may readily be assembled, and considerable 35 deflection between adjacent lengths of pipe is provided for, while at the same time said filler is adapted to prevent entrance of the fibrous material into the interior of the pipe beyond the end of the spigot.

40 And a still further object is to provide for the use at the mouth of the bell of malleable material which need not be reduced to a molten or plastic condition in order to put it in place initially.

45 The means by which the foregoing and other objects are accomplished by my invention, and the manner of their accomplishment, readily will be understood from the following description on reference to the accompanying drawings, in which:—

Fig. 1 is a view of a preferred form of my improved pipe joint, half in section and half in side elevation.

50 Fig. 2 is a section on the line II—II of Fig. 1.

As shown in the drawings, in which corresponding parts are identified by like reference numerals throughout the several views, the pipe 5 is provided with a bell end 6, adapted to receive the spigot end 7 of the pipe 8. 60 At the base of the interior of the bell is an annular shoulder 9, having a plane face which is inclined outwardly toward the mouth of the bell, the interior surface of the bell above said shoulder being cylindrical at 10, being inclined outwardly toward the mouth of the bell to form a frusto-conical surface at 11, and being inclined inwardly to form the interior flange or shoulder 12 at the mouth of the bell. 65

The filler ring 13 preferably is formed of a 70 substantially unyielding material such as steel or cast iron, and is of one-piece construction, having a cylindrical body portion terminating at one end in an inclined surface 14, the inclination of which substantially conforms 75 with that of the shoulder 9 at the base of the bell, and said ring terminating at its other end in a double-wedge-shaped portion 15, the faces of which preferably are inclined toward each other at the same angle relative 80 to the inner and outer surfaces, respectively, of the body portion of the ring, so that said inclined faces are of substantially the same area. The length of the filler ring preferably is such that, when its inclined surface 14 is 85 resting upon the shoulder 9 at the base of the bell, the wedge-shaped portion 15 stands at the base of the flaring surface 11.

Fibrous material 16, such as jute or hemp, is interposed between the filler ring 13 and 90 the packing 17 of malleable metal, such as lead, at the mouth of the bell. Preferably, said packing is initially put in place in the form of a unitary ring, instead of being poured into the joint in a molten condition, 95 and is subsequently tightened in place with a calking tool or the like, and thereby distorted sufficiently to fill the groove between the shoulder or interior flange 12 at the mouth of the bell and the outer part of the frusto-conical surface 11. The filler ring 13 has an interior diameter sufficiently larger than the exterior diameter of the spigot 7, and an exterior diameter sufficiently smaller than the interior diameter of the bell 6, so that said 100 ring may readily be slipped over said spigot and inserted in said bell, and the desired amount of "play" of the spigot in the bell is provided for, while at the same time the filler ring fills the space between the spigot 105 and the bell. 110

and the bell sufficiently to prevent the fibrous material from being forced past said ring and into the interior of pipe 5.

In assembling the parts of my improved joint, the lead packing ring 17 is placed over the spigot end 7 of pipe 8; the filler ring 13 is placed in the bell, with its wedge end 15 directed toward the packing ring and its bevelled end 14 bearing against the inclined shoulder 9; the spigot is entered in the bell until the end of the spigot takes against the inclined shoulder 9 of the bell; the jute or other fibrous material 16 is tamped into the space between the spigot and the bell, over the wedge end of the filler ring; the packing ring is slipped into place over the tamped fibrous material, and is driven against said material, and calked so as to expand it inwardly against the spigot and outwardly into the groove at the mouth of the bell. The fibrous material is readily compressible, and if forced, by the calking of the lead packing, against a **filler** which opposes a substantially plane surface to the fibrous material, said material tends to be compacted longitudinally of the space in which it is confined, and to be to only a limited extent pressed against the outer surface of the spigot and the inner surface of the bell. But by the use of a **filler** which opposes a wedge-shaped surface to the fibrous material, compression of said material causes it to become wedged tightly between the **wedge end 15 of the filler ring** and the opposed surfaces of the spigot and the bell; also, the extent of this wedging action in the two directions is given the desired uniformity by the employment of a double wedge, the two faces of which are preferably inclined to substantially the same extent and have substantially the same area.

It will be noted that my improved pipe

joint is not "precalked", which is a term that is recognized in this art as applying to a joint in which, before the spigot is placed in the bell, the lead or other packing material is calked sufficiently to retain the filler and the fibrous material in place; but my joint may correctly be described as being "prepared" or "made ready", in the sense that the filler ring, the packing ring, and the fibrous material, may be assembled in their ultimate positions, after the spigot is entered in the bell, without any treatment at the time of being assembled, other than the calking of the packing ring.

Various modifications of minor details of the improvements disclosed herein doubtless readily will suggest themselves to those skilled in this art, but such modifications fall within the scope of my inventive rights, and my invention is not to be construed as being limited to any details not specifically set out in the claim.

Having thus fully described the invention, what I claim as new, and seek to secure by Letters Patent, is:—

A joint for bell and spigot pipe, comprising a rigid **filler ring** mounted between the bell and spigot at the base of the bell and having its outer upper edge bevelled from both inner and outer periphery to provide a sharp double wedge-shaped edge, a wedge shaped recess formed on the inner face of said bell adjacent to said bevelled edge, a fibrous packing disposed to engage said wedge end of the **filler ring**, and malleable packing material forced into the outer end of the bell to seal the joint and tightly compact the fibrous packing material against the ring and into the wedge shaped recess on each side of its wedge-shaped end.

In testimony whereof I affix my signature.

WALKER REYNOLDS.
